UNITED STATES PATENT OFFICE.

GUY CARLETON DENNEY, OF HINSDALE, ILLINOIS, ASSIGNOR TO AMERICAN ARCH COMPANY, A CORPORATION OF DELAWARE.

FIRE-BOX-ARCH CONSTRUCTION.

Application filed November 26, 1920. Serial No. 426,348.

To all whom it may concern:

Be it known that I, GUY CARLETON DENNEY, a citizen of the United States, residing at Hinsdale, in the county of Du Page 5 and State of Illinois, have invented certain new and useful Improvements in Fire-Box-Arch Constructions, of which the following is a specification.

This invention relates to refractory 10 arches for boiler fire boxes and particularly to such arches as they are applied to standard locomotive fire boxes equipped with circulation or arch tubes.

It has for one of its primary objects the 15 provision of means whereby it is possible to greatly increase the adaptability of arch bricks of a given size to various tube settings in which the distance between tubes may substantially vary within reasonable limits. 20 Stated in other words, it is the object of my invention to provide means whereby an arch composed of a plurality of bricks of a uniform size can be applied to or supported by a plurality of tubes the distances between 25 which may not be uniform.

Another of the objects of my invention is the provision of a construction whereby all possibility of distortion of the circulation tubes due to the wedging action of certain 30 bricks more particularly side or wing bricks, is eliminated.

More specifically stated, my invention contemplates the provision of a plurality of supporting members for the bricks of the 35 arch which are interposed between the tubes and the bricks, each member being adapted to rest upon a single tube and being constructed with a tube engaging surface and with a brick supporting surface, the latter 40 of which can swing about the tube to one side or the other of the vertical so as to bring it into proper position for support of a brick in cases where the tube spacing is less than or greater than the normal distance for 45 which such brick is intended.

It should be noted that my invention is particularly useful in connection with an arch, the bricks of which are intended to be laid flat upon the tubes and in which each 50 brick spans the distance between tubes. Such an arch is now well known in the art as a "Security" arch and my invention is illustrated in the accompanying drawing in association with an arch of this character.

55 The foregoing objects, together with such

other objects as may appear hereinafter or are incident to my invention I obtain by means of the construction illustrated, where in:

Fig. 1 is a somewhat diagrammatical longitudinal section through a locomotive boiler fire box embodying my invention, taken through an arch as indicated by the line 1-1 in Fig. 2; and Fig. 2 is a section on the line 2-2 of Fig. 1.

Referring to the drawing, the locomotive fire box A therein illustrated is shown as of usual construction comprising the crown sheet 1, flue sheet 2 extending downwardly into the throat sheet 3, the inside back sheet 4, the outside back sheet 5 and the two inside side sheets 6 and 7. A plurality of circulation or arch supporting tubes 8 connect the forward water leg 17 with the rear water leg 18, four tubes being illustrated. The 70 usual average distance between said tubes in many typical fire box constructions is 16", as indicated at the right in Fig. 2.

This distance, of course, may vary slightly in different tube settings, and ordinarily 80 such small variations are compensated for by the inclined surfaces 9 on the center bricks 10. Wing bricks 11 extend from the outer tubes to the inside side sheets as shown. A construction such as shown in this figure 85 with the bricks resting directly upon the tubes has heretofore been standard practice.

Should the distance between any two tubes be substantially increased or decreased, it has heretofore been customary to compensate therefor, either by the use of larger or smaller bricks or by replacing the single bricks 10 with pairs of smaller bricks between the tubes arranged in arched relation, with their inner ends resting against each 90 other. In accordance with my invention, I overcome the necessity for such modifications by the provision of means whereby a center brick of a given size, such, for example, as that illustrated in Fig. 2 which 100 for convenience is termed a 16" brick, may be adapted for use in connection with a 15" or a 17" tube spacing as well as a 16" spacing. It will be understood, of course, that these dimensions are merely arbitrary; for 105 it will be readily apparent that the same principle could be applied to bricks and tube spacings of other dimensions.

In Fig. 2 it will be seen that the tubes are 110 variously spaced, the distance between tube

8 and 8^a being 17", that between tubes 8^a and 8^b 15" and that between tubes 8^b and 8^c 16" as indicated. In this figure I have interposed between the tubes and the ends of the bricks a series of blocks which I have termed supporting members or saddle bricks 12. These supporting members are provided with a tube engaging recess or socket 13 in their lower faces and with a curved brick 10 supporting portion and surface 14 on their upper faces. Both of these surfaces conform to the curvature of the tubes and they are struck from centers which place the brick supporting surface directly above the tube engaging socket or surface 13. By tilting the supporting member 12 on the tube 8^a toward the left it is possible to move the brick supporting surface 14 sufficiently toward the tube 8 and away from the tube 8^b to make it possible to employ bricks 10, of the same size as those illustrated in Fig. 3, to span the 17" space between tubes 8 and 8^a and the 15" space between tubes 8^a and 8^b, as clearly shown in the drawing. By this means a 16" brick, for example, can be accommodated to a 17" or a 15" tube spacing as well as to a 16" tube spacing. The bricks 10 are provided with a support engaging socket 15 at the end opposite the inclined surface 9 and it will be obvious that this socket or recess 15 will snugly fit the brick supporting surface 14 on the member 12 whether such member be vertically disposed as on the tubes 8, 8^a and 8^c or inclined as on the tube 8^a. The body portion of the member 12 below the brick supporting portion or surface 14 is cut away or sloped as at 16 so as to leave the portion 14 free flanked, and obviate interference with the lower surface of the bricks 10 in places where the supporting members are tilted. Thus the member 12 and its supporting portion and surface 14 adapt and accommodate themselves freely and fully to the varying angular relations of brick 10 and member 12 entailed by the swing or tilt of the latter with variations or differences in tube span or brick length.

My improvement is also very useful in connection with the side or wing bricks 11 herein illustrated. In ordinary practice (see Fig. 3) the inner ends of the wing bricks rest directly on the tubes and the outer ends against the side sheets, and, especially where such bricks are large and heavy, there is sometimes a tendency to distort or bend the tubes due to the wedging action between them and the side sheets. This wedging action becomes greater as the planes of the wing bricks approach more closely the horizontal. But, where my improved supporting members or saddle bricks are used and the inner ends of the wing bricks are supported thereon, as shown in Fig. 2, the force of whatever wedging action there may be will not be exerted in a straight line di-

rectly on the tubes but on the upper portions of the saddle bricks, which latter will tend to rotate slightly until a condition more nearly approaching equilibrium is reached between the force exerted by the wing bricks and that exerted by the adjacent center bricks on the opposite side of a given tube. Possible distortion or bending of the tubes is thereby eliminated.

I claim:

1. In a locomotive fire box having spaced arch supporting members, an arch comprising brick supporting members on the arch supporting members and bricks spanning the distance between said arch supporting members and resting on said brick supporting members, each of said brick supporting members being provided with an arch supporting member engaging surface and a brick supporting surface, the arch supporting member engaging surface permitting movement of the brick supporting member to change the position of the brick supporting surface whereby spaces of different dimension between arch supporting members can be spanned by bricks of one size.

2. In a locomotive fire box having circulation tubes, the combination with an arch composed of a plurality of bricks supported thereby, of supporting members for said bricks having a brick supporting surface and a tube engaging surface, said tube engaging surface permitting the supporting member to swing on the tube so as to vary the position of the brick supporting surface.

3. In a locomotive fire box having spaced arch supporting members, the combination with an arch composed of a plurality of bricks, of supporting members for said bricks having a brick supporting surface and a support engaging surface, said latter surface permitting movement of the supporting surface whereby bricks of one size can be accommodated to varying spaces between the arch supporting members.

4. In a firebox, the combination with arch supporting tubes, of an arch composed of a plurality of bricks, and supporting members for said bricks with tube engaging surfaces permitting the members to swing on the tubes and arch brick engaging surfaces free-flanked to obviate interference of the bricks with such swinging.

5. In a locomotive fire box having arch supporting tubes, the combination with an arch composed of a plurality of bricks, of supporting members for the bricks adapted to be interposed between the tubes and the ends of the bricks, each of said supporting members being provided with a tube engaging recess permitting it to assume varying angular positions on the tube and each having a brick supporting surface which substantially corresponds to the surface of the tube in curvature whereby bricks of one size

can be accommodated to varying tube spacings.

6. A supporting member for the bricks of a tube supported locomotive arch having a tube engaging surface and a brick supporting surface, both of said surfaces being substantially semicircular and having substantially the same radius as the tube and the tube engaging surface being adapted to permit the supporting member to be swung on the tube to move the brick supporting surface to one side or the other of the tube.

7. A supporting member for the bricks of a tube supported locomotive arch having a tube engaging surface and a brick supporting surface, the brick supporting surface being arranged substantially directly over the

tube engaging surface and the tube engaging surface being constructed to permit the supporting member to be swung on the tube to move the brick supporting surface to one side or the other of the tube.

8. A supporting member for the bricks of a tube supported locomotive arch having a tube engaging surface adapted to permit the member to swing on the tube, and a free flanked brick engaging surface moving sideways relatively to the tube as the member swings, and adapted to the varying angular relations of brick and supporting member entailed by such swinging.

In testimony whereof, I have hereunto signed my name.

GUY CARLETON DENNEY.
